UNITED STATES PATENT OFFICE.

WILLIAM LIPPS, OF RIDGEDALE, TENNESSEE.

WINDLASS WATER-ELEVATOR.

SPECIFICATION forming part of Letters Patent No. 729,618, dated June 2, 1903.

Application filed March 20, 1903. Serial No. 148,743. (No model.)

To all whom it may concern:

Be it known that I, WILLIAM LIPPS, a citizen of the United States, residing at Ridgedale, in the county of Hamilton and State of Tennessee, have invented certain new and useful Improvements in Windlass Water-Elevators; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to windlass water-elevators, and has for its object a well-fixture in which the water is automatically emptied as the bucket reaches the top. The invention comprises, broadly speaking, a bucket having a valve and a swinging pan which is actuated by the bucket to open the valve and cause the water to discharge thereinto, which conducts it to a trunk on the outside of the well-casing.

25 The object of the invention is to provide a simple and effective device to accomplish this purpose.

Improved details of the construction and arrangement of the several parts of the invention will be apparent from the detailed description hereinafter and the appended claims, when read in connection with the accompanying drawings, forming part hereof, in which—

35 Figure 1 is an elevation of the outside of the well-casing. Fig. 2 is a side elevation of the operating mechanism, one side of the well-casing being removed. Fig. 3 is a similar view partly in section. Fig. 4 is a rear elevation. Fig. 5 is a sectional view of the well-bucket.

Referring specifically to the drawings, 6 indicates a well-casing having near the top thereof a ventilating-screen 6^a, which also 45 serves to prevent insects, &c., from entering the well, and thus contaminating the water. A pulley 7, mounted near the top of the casing, carries the operating rope or chain 8, from which the buckets 9 are suspended. The pulley-shaft 7^a extends through the casing and has a suitable crank 7^b and a pawl and ratchet 7^c to prevent slipping. The buckets 9 have

at the bottom an opening 9^a, which is normally closed by a valve 10, having a stem 10^a, which projects below the bottom of the bucket. 55 A discharge-pan 11 for each bucket is hinged, as at 11^a, to the well-casing. These pans are adapted to be swung upward to open the valve in the bucket and conduct the water to a trunk 12 on the outside of the well-casing. 60 Rods 13 are secured to the pans 11 by hooking into eyes 13^a or in any other suitable manner. The upper ends of these rods extend loosely through a slot in a beam 14, extending across the well-casing—this for the purpose 65 of guiding the rods and steady their movements. A block 15 is slidably mounted on the rods 13 and is secured thereto by set-screws 16. This block carries a yoke 17, which extends outward from the rod to embrace the 70 rope 8. The pans normally hang down out of the path of the buckets.

The operation of the device is as follows: When the bucket is raised, the upper edge of it will strike the yoke 17 and cause the pan 75 11 to be swung up and extend through an opening 6^b in the well-casing and into the trunk 12. When the pan is raised to the proper height, the valve-stem 10^a will be engaged thereby and the valve raised from its 80 seat. The water will then flow out of the bucket into the pan, which will conduct it to the trough 12. The rods 13 also serve to steady the bucket as it rests on the pan. The block 15, which carries the yoke 17, is adjustable on the rods 13, as heretofore stated, so that different-size buckets may be used.

I have shown two buckets, so that while one is being filled the other empties; but my device may be applied to a well in which one 90 bucket only is used.

Having thus described my invention, what is claimed as new, and desired to be secured by Letters Patent, is—

1. A well-fixture comprising a casing, a 95 valved bucket, means for raising and lowering the same, a discharge-pan hinged to the casing, rods secured to the pan, a beam extending across the casing having guide-slots through which the rods extend, and an adjustable block on the rods having a yoke adapted to be actuated by the bucket for elevating the pan to open the bucket-valve, substantially as described.

2. A well-fixture comprising a casing, a valved bucket, means for raising and lowering the same, a discharge-pan hinged to the casing, a trunk outside the casing into which the pan discharges, rods secured to the pan, a beam extending across the casing having guide-slots through which the rods extend, and an adjustable block on the rods having a yoke adapted to be actuated by the bucket

for elevating the pan to open the bucket-valve, substantially as described.

In testimony whereof I affix my signature in presence of two witnesses.

WILLIAM LIPPS.
